UNITED STATES PATENT OFFICE.

HENRY W. CARPENTER, OF WASHINGTON, DISTRICT OF COLUMBIA, ASSIGNOR TO AMERICAN WOVEN LATH COMPANY, OF WASHINGTON, DISTRICT OF COLUMBIA, A CORPORATION OF WEST VIRGINIA.

SLAT-WEAVING MACHINE.

No. 877,904.

Specification of Letters Patent.

Patented Feb. 4, 1908.

Application filed May 5, 1906. Serial No. 315,414.

To all whom it may concern:

Be it known that I, HENRY W. CARPENTER, a citizen of the United States, residing at Washington, in the District of Columbia, 5 have invented new and useful Improvements in Slat-Weaving Machines, of which the following is a specification.

This invention relates to a machine for weaving wooden slats to form woven wooden 10 lathing, and the method involved thereby.

The general object of the invention is to provide a machine in the use of which the entire series of warp slats entering into the construction of a section of lathing may be 15 simultaneously provided throughout their length at suitable intervals with sheds, and the entire series of weft slats may be simultaneously fed into and through the respective lines of sheds, or openings, whereby a complete section of lathing may be made in one 20 cycle of operation of the machine.

Detailed objects of the invention relate to novel mechanism for effecting the operation of the machine in stages; to novel mechanisms 25 for feeding the warp and weft slats to the shed-forming press; to novel mechanisms for effecting the delivery of the completed lathing sections from the press; and to a novel construction of press for forming the 30 sheds in the warp slats and for insuring the unobstructed feed of the weft slats therethrough.

In addition to the above-stated general and specific objects of the invention, other 35 and further objects relate to details of construction and to combinations, arrangements and operations of parts, all as herein-after more fully described and particularly pointed out in the claims.

40 The invention is illustrated in the accompanying drawings in which:

Figure 1 is a plan view of a slat weaving machine constructed in accordance with my invention, a portion of the upper member of 45 the press being broken away to better illustrate the construction; Fig. 2 is a longitudinal sectional view on the line 2—2 of Fig. 1; Fig. 3 is a transverse sectional view on the line 3—3 of Fig. 1; Fig. 4 is a view in end elevation of the inner end of the feed-table for the warp slats; Fig. 5 is an enlarged view in elevation, looking in the direction of the arrow 5 of Fig. 1, showing one end-portion of the shed-forming press, with the upper member 50 thereof raised, and the adjacent portion of

the feed-table for the warp slats, said view illustrating one position of the delivery mechanism and of the feed mechanism; Fig. 6 is a view similar to Fig. 5, the upper member of the shed-forming press being down, 60 and illustrating a different position of the delivery and feed mechanisms to that shown in Fig. 5; Fig. 7 is an enlarged view in elevation, looking in the direction of the arrow 7 of Fig. 1, showing one end portion of the feed-table for the weft slats and the adjacent portion of the shed-forming press, the upper member of the latter being raised, said view illustrating one position of the feed mechanism for the weft slats and of one of the devices for lifting the completed lathing from the bed of the press; Fig. 8 is a view similar to Fig. 7, the upper member of the press being down, and illustrating a different position of the weft-slat feeding mechanism and 65 of the lifting device to that shown by Fig. 7. Fig. 9 is a top plan view on an enlarged scale of a portion of the lower member, or bed, of the shed-forming press; Fig. 10 is a section taken on the line 11—11 of Fig. 9; and Fig. 70 11 is a section taken on the line 12—12 of Fig. 9, the latter two figures showing the corresponding portions of the upper member of the shed-forming press, and Fig. 10 showing, in section, the relative positions of the 75 warp slats, and, by dotted lines, of a weft slat, after a weaving operation.

Referring now to these drawings, 12 indicates the lower member, or bed, of the shed-forming press, which is supported on 90 standards 13, and 14 indicates the upper member of said press.

The numerals 15 indicate uprights arranged at the respective corners of the shed-forming press, but at a distance therefrom, 95 each of said uprights being grooved on its inner side as indicated at 16, Fig. 2, to form guides. 17 indicate cross-bars extending between respective pairs of uprights 15 and working at opposite ends in the guide grooves 100 16 of said uprights. Secured to each of said cross-bars 17, near opposite ends thereof, are castings 18 which are in turn secured to the upright member 14 of the shed-forming press at the respective corners thereof. Depending 105 from opposite ends of each cross-bar 17 and also slidably engaging in the grooves 16 are slide-bars 19, each of which has an enlarged lower end-portion 20 provided with a rack-bar 21. 110

In the operation of the machine the upper member 14 of the press must be raised and lowered, and the means for accomplishing this result will now be described:

22 indicates the main driving-shaft supported in suitable bearings 23 and extending throughout the entire length of the machine and beyond opposite ends thereof. 24 indicates a pulley affixed to one end of said shaft, by means of which it may be driven from a suitable source of power (not shown). Mounted on the shaft 22, slightly beyond opposite ends of the shed-forming press, are two mutilated gears 25, each of which has gear teeth correspondingly arranged and extending over a quadrant of a circle, as indicated at 26 in Fig. 3. Mounted in a bearing at the opposite end of a support 27, located adjacent to each of the mutilated gears 25, is a shaft 28 on the inner end of which is a bevel gear 29. Mounted in bearings at the upper ends of supports 30 is a shaft 31, having secured at opposite ends bevel gears 32—33, respectively. Secured on each of the shafts 28 is also a mutilated gear indicated, respectively, by the numerals 34 and 35, each of said mutilated gears having on diametrically opposite sides a series of gear-teeth extending over the quadrant of a circle. One set of the gear-teeth on each of the mutilated gears 34—35 is adapted to engage with the corresponding rack-bar 21, and the other set is adapted to be engaged by the toothed portion 26 of the mutilated gear 25.

It will be understood that the mechanism shown in Fig. 3, comprising the mutilated gear 25 with the co-operating mutilated gears and bevel gears for actuating the two slide-bars shown in said figure, are duplicated at the other end of the machine, as indicated by Fig. 2, for operating in synchronism the other two slide-bars 19.

As thus far described, as the shaft 22 rotates in the direction of the arrow, indicated by Fig. 3, the teeth 26 of the mutilated gear 25 will engage the one set of teeth of the mutilated gear 34, thereby causing the other set to engage with the adjacent rack-bar 21. As the mutilated gear 34 is revolved the bevel gear 29, which is fastened on its shaft and which meshes with the bevel gear 32, will cause the shaft 31 to be rotated, and the bevel gear 33 thereof, meshing with the other bevel gear 29, will cause the mutilated gear 35 to be revolved in the direction indicated by the arrow, and one set of its teeth to engage the other rack-bar 21. At the same time the corresponding mechanism for operating the second set of rack-bars is simultaneously operated from the shaft 22, and by this means the slide-bars 19 will be raised, and accordingly raise the upper member 14 of the shed-forming press. As the mutilated gears 25 continue to revolve, their toothed portion 26 will next engage the other set of

teeth on the mutilated gears 35, thereby reversing the original direction of the movement of said gears, and through the instrumentality of the sets of bevel gears 29, 33, 32 and 29 reverse the previous direction of the movement of the mutilated gears 34. In such direction of the movement of these latter gears, their set of teeth first named will engage the rack-bars and draw them downward, thereby lowering the upper member 14. Thus in the revolution of the shaft 22, the member 14 will first be raised and then lowered and again raised, and so on as long as the machine is in operation. When the upper member 14 of said shed-forming press is raised, the machine operates to feed the warp-slats inward upon the bed 12, and the mechanism for accomplishing this operation will now be described:

Mounted on supports 36 is a table 37 supported from opposite sides of which, by means of brackets 38, is a rectangular frame 39 which is located directly over the table 37 but is supported by the brackets 38 out of contact with said table, a space 40 between said table and frame being provided which is equivalent in height to the thickness of a warp-slat. Secured in opposite ends of the frame 39 are a series of partitions 41, which are the same height as the frame 39, and in common therewith are supported in a vertical position above the upper surface of the table 37, a distance equal to the thickness of a warp-slat. The partitions 41 divide the frame 39 into a series of receptacles 42, fifteen of such receptacles being shown.

Mounted in bearings 43, carried by brackets 44, secured on the under side of the table 37 toward the outer end thereof, is a shaft 45 on which are mounted two sprocket-wheels 46. Suitably mounted in bearings at the opposite ends of the table is a shaft 47, on which are mounted two sprocket-wheels 48, which are in line with the sprocket-wheels 46. Mounted on respective sets of sprocket-wheels 46 and 48, are sprocket chains 49, which work in longitudinal grooves made in the upper surface of the table 37, near opposite sides thereof, as indicated by the dotted line in Fig. 2; and connected to and extending between these sprocket chains at suitable distances apart, are two feed-bars 50—51, which are substantially the thickness of a warp-slat, and are adapted to work through the space 40, above described, in order to sweep the lower slat of each receptacle 42, which will rest upon the table 37, into the shed-forming press by rotating the shaft 45.

In order to provide for the movement of the sprocket chains 49, I secure on a projecting end of the shaft 45 a sprocket-wheel 52 over which passes a sprocket chain 53, which chain also passes over a sprocket-wheel 54 mounted on the outer end of a

shaft 55 suitably supported in bearings on supports 56. On the inner end of the shaft 55 is a bevel gear 57 which is adapted to be engaged by the toothed-portion 58 of a mutilated gear 59 mounted on the shaft 22, all as clearly illustrated in Figs. 1 and 2. The toothed-portion 58 extends over a quadrant of the mutilated gear 59. Thus as the shaft 22 revolves in the direction of the arrow indicated in Fig. 1, the toothed-portion 58 of the mutilated gear 59 will in time engage the teeth of the bevel gear 57, thereby rotating the shaft 55 and the sprocket chains 53, which will in turn cause the rotation of the shaft 45, this movement continuing as long as the teeth 58 engage with the teeth of the gear 57, and ceasing as soon as said teeth pass out of engagement with said bevel gear. The relative positions of the feed-bars 50-51, when the teeth 58 have passed out of engagement with the bevel gear 57, and the movement of the sprocket chains 49 ceases, is shown by Fig. 2, from which it will be seen that the feed-bar 51 has been moved out from under the frame 39 and part of the way around the sprocket-wheel 48, while the feed-bar 50 is in a position to pass under the frame 39, when the teeth 58 again engage the teeth of the bevel gear 57. The sprocket chains and feed-bars described will operate to feed the warp-slats into the press almost the entire distance they should go, but it is obvious that said feed-bars can not push the slats the entire distance necessary, as to do this the said feed-bars would have to engage the end of the shed-forming press, owing to the arc described by said feed-bars in passing over the sprocket-wheels 48; and in order to complete the feed of the warp-slats, I provide the following mechanism, reference being had more particularly to Figs. 2, 3, 4, 5 and 6 of the drawings:

Mounted on the inner end of the frame 39 in opposite sides thereof are two bars 60, in which are supported a rock-shaft 61. Fixedly secured at three or more points to the shaft 61 are arms 62 which support a bar 63. Fixedly secured on one end of the shaft 61 and curved inwardly toward the table 37 is a cam finger 64 which is normally pulled inward toward the table 37 by means of a coiled spring 65. As shown by Fig. 1, one end of the feed-bar 50 (and of course the feed-bar 51) projects slightly beyond the side of the table 37, each projecting portion being indicated by 66. This projecting portion 66 of the feed-bars is adapted, in the movement of the sprocket chain 49, to engage the cam finger 64 to rock the shaft 61. This occurs immediately after the feed-bar has passed out of contact with the ends of the warp-slats. Thus, as indicated in Fig. 5, the feed-bar, say 50, has moved the warp-slats 67 onto the bed 12 of the press and is

about to pass out of contact with the ends of said warp-slats to pass around the sprocket-wheels 48. In this latter movement the projecting end 66 will engage the cam finger 64 and move it outward, and in so doing rock the shaft 61, thereby lowering the arms 62, carrying the bar 63 outward or away from the table 37, and bringing the bar 63 into engagement with the inner ends of the warp-slats 67, and this movement continues, as shown by Fig. 6, until the warp-slats have been pushed entirely onto the bed 12 when the projection 66 will pass out of engagement with the cam finger 64 and the latter will be returned to the normal position shown by Fig. 5. The curve, or cam surface of the finger 64 is such that the projection 66 of the feed-bar will readily pass over the same without binding but will operate by the engagement therewith, and in describing the arc of a circle necessary in passing around the sprocket-wheels 48, to move said cam finger outward and feed the warp-slats onto the table as described, and then to freely pass off of said cam finger.

The next step in the operation of the machine is to form the sheds in the warp-slats in order to permit the weft slats to be fed between the same for interweaving therewith, and to this end the opposing surfaces of the upper and lower members of the press are provided with shed-forming members, shown partially in several of the figures, but more clearly illustrated in Figs. 9, 10 and 11. Referring first to the bed 12, the same is composed of a number of longitudinal bars 68 which may be glued or otherwise secured together at their lower portions, but which are separated by a space of about a quarter of an inch at their upper portions as indicated at 69, said spaces being provided by grooving out the contiguous portions of adjacent bars. The upper surface of each bar 68 is provided throughout its length with a series of alternating curved projections 70 and corresponding depressions 80, the projections and depressions of the series of bars being arranged in staggered relation, as clearly indicated in the figures named. Each of the curved projections 70 is provided with a rectangular, transverse slot 81 which has its outer or front edges beveled or flared to permit the easy entrance of the weft-slats as indicated at 82. The upper member or leaf 14 of the shed-forming press is composed of a series of bars 83 in the same manner as the bed, and each of these bars is also formed on its outer surface throughout its length with a series of alternating curved projections 84 and corresponding depressions 85, and each of the projections 84 has a transverse rectangular slot 86 having beveled or flared openings 87 in the same manner as described with respect to the slots of the bed. The projections and depressions of the bars 83 of the

upper member 14 are arranged in staggered relation in the same manner as described with respect to the like parts on the bed, each of the bars 83 being directly above and 5 extending parallel to a bar 68, and the curved projections on each opposing bar being disposed opposite, or immediately above or below, the corresponding curved depression of the other bar. In other words, the curved 10 shed-forming projections 70 of the bed are arranged in staggered relation to each other and to the like series of projections 84 of the upper member 14 of the press.

At suitable intervals throughout the length 15 of the bed 12, I secure in the spaces 69, preferably on each side and at each end of the slots 81, guide plates 88 which project upward at suitable distance above the curved projections 70, and are for the purpose of 20 guiding the warp-slats 67 as they are fed onto the bed, said slats passing in between the guide plates as clearly illustrated in Fig. 10. As the upper member 14 descends, the 25 guide plates 88 are received into grooves 89 formed between the bars 83 of said upper member as shown.

With the two members of the press constructed as described, it will be seen, referring to Fig. 2, that the warp-slats having 30 been inserted, when the upper member 14 is lowered, said warp-slats will be bent in alternately reverse directions throughout their length and with respect to each other, and that the slots 80 and 86 will form continuous 35 transverse passages through the press to enable the weft-slats to be inserted between the sheds formed in the warp-slats. The mechanism for this purpose will now be described: 90 indicates a table which is located 40 at one side of the shed-forming press at right angles to the table 37, and is provided with a frame 91 and partitions 92 in the same manner as described with reference to said table 37, said partitions 92 forming a series of receptacles 93 for the weft-slats which are piled in said receptacles one on top of the other, the lowermost slat resting on the upper surface of the table 90. 94 indicates the space 45 between the bottom of the frame 1 and of the partitions 92 corresponding to the space 40 of the table 37. On the rear end of the table are mounted brackets 95 providing bearings 96 for a shaft 97, on which shaft are mounted sprocket-wheels 98. At the front end of the 50 table is mounted in a similar manner a shaft 99 on which are mounted two sprocket-wheels 100. Sprocket chains 101 pass over the respective sets of sprocket-wheels 98 and 100. On a projecting end of the shaft 97 is 55 mounted a sprocket-wheel 102. Mounted in suitable bearings 103 at the opposite end of the shed-forming press to that at which the table 37 is located is a shaft 104, on which is mounted a gear-wheel 105 and a sprocket-wheel 106. A sprocket chain 107 passes

over the sprocket wheels 102 and 106. On the main driving shaft 22 is mounted a mutilated gear 108, one quadrant of said gear being provided with teeth 109, which are adapted in the rotation of said mutilated gear to mesh with the teeth of the gear-wheel 105. By such means and through the medium of the sprocket chain 107 the shaft 97 is rotated intermittently to impart movement to the sprocket chains 101. Said 70 sprocket chains run in grooves in the table 90, as more clearly appears from Figs. 7 and 8, and are connected by feed-slats 110 and 75 111, the purpose of which feed-slats is to sweep over the surface of the table 90 and 80 remove the lowermost slat in each receptacle 93, and cause its part insertion into the shed-forming press and between the sheds of the warp-slats. For the reasons previously described with reference to the feed mechanism of the warp-slats, the feed-slats 110 do not cause the weft-slats to be entirely inserted in the press, and this feed is completed in the same manner as described with 85 reference to the warp-slats, and as clearly 90 indicated in Figs. 7 and 8, in which 112 indicates a shaft supported on brackets 113 on the inner side of the frame 91, said shaft having fixed thereon arms 114 carrying at their lower ends a bar 115, which is adapted 95 to engage the ends of the slats to press them entirely within the press, as clearly indicated in Fig. 8. 116 indicates the cam finger which is adapted to be engaged by a projecting end 117 of each of said feed-slats, thereby causing the movement of the bar 115 100 in precisely the same manner as heretofore described with reference to the mechanism shown in Figs. 5 and 6.

In the operation of the machine, assuming 105 the upper member of the press to have been lowered, as in Figs. 3 and 4, and the weft-slats to have been fed in, the next movement will be to raise the upper member 14, and this is done in the revolution of the main 110 shaft 22 when the gear-teeth 26 of the mutilated gears 25 engage one quadrant of teeth on the mutilated gears 34 (Figs. 2 and 3). The next operation will be the feeding of the 115 warp-slats into the press, which occurs when the teeth of the mutilated gear 59 come into mesh with the beveled gear 57. The next cycle is to lower the upper member 14, and this is done by the teeth of the mutilated gears 26 coming into mesh with one 120 quadrant of teeth on the mutilated gears 35. The last step in forming the slat is to feed the weft-slats through the sheds formed in the warp-slats, and this is done by the engagement of the teeth of the mutilated gear 125 108 with the gear-wheel 105. Thus it will be seen that the machine is operated in a continuous manner but in successive stages by a single driving-shaft, owing to the relative location of the quadrants of gears on the 130

various mutilated gear-wheels described. It may be stated that the frictional contact of the slide-members 19 and cross-bars 17 in the guide grooves of the standards 15, added 5 to the contact of the gears, is sufficient to maintain the upper member 14 elevated after the mutilated gears 26 have passed out of engagement with the quadrants of teeth of the mutilated gears 34.

10 The final stage in the manufacture of the lathing, so far as this application is concerned, is the removal of said lathing from the press, and this I do automatically, as illustrated more clearly in Figs. 1, 2, 3, 4, 7, 15 and 8.

Pivots mounted near the four corners of the upper member 14 of the press, as indicated at 117, Figs. 7 and 8, are four catch-levers 118 having lower hooked ends 119, 20 which when the catch-levers are in a vertical position project slightly within the lower edge of said upper member 14. Each of these catch-levers 118 is provided above its pivot point with a projecting inclined surface 120, affording at its upper end a shoulder 121. Mounted in suitable bearings 122 on the upper side of the upper member 14 is a rock shaft 123 on which are secured two sets of oppositely directed crank-arms 124, the outer 25 end of each crank-arm being connected by means of a rod 125 to the upper end of a catch-lever 118. Pivots secured on the shaft 123 is an arm 126 which is adapted, after the upper member 14 has been raised a 30 given distance to engage the under side of a fixed stop 127, secured to and projecting inward over the press from a beam 128 extending between two of the uprights 15 located on the opposite side of the table to that at which 35 the table 90 is located. It is obvious that with the catch-levers 118 in a vertical position and with their hooked ends projecting inward beneath the lower edge, as the upper member 14 of the press was lowered, the lower 40 hooked ends of said catch-lever would engage the edge slats on the bed of the press and disarrange them. In order to obviate this I mount on the frame 91 in line, respectively, with the two catch-levers 118 on that 45 side of the press arms 129, which are secured to the frame 91 by means of a hinge 130, and so as normally to be held by gravity in a horizontal position. As the upper member 14 descends, before the hooked ends 119 can 50 come in contact with the slats on the bed the inclined projecting surface 120 at the upper ends of the two catch-levers described will engage the outer ends of the two arms 129 and cause the lower ends of said catch-levers 55 to be thrown outward or away from the side of the press. When the upper member 14 has entirely descended the arms 129 will pass off of the inclined surface 120 and the shoulder 121 will pass under said arms and 60 allow the catch-levers 118 to swing inward.

This movement is caused by a coiled spring 131, one end of which is secured to the top of the upper member 14 of the press and the other end of which is secured to a crank-arm 132 on the rock-shaft 123, the spring normally holding the said catch-lever 118 inward. This position of the catch hooks is indicated in Figs. 3 and 8.

As indicated by dotted lines in Fig. 8, the sides of the bed 12 are suitably grooved to 75 permit the entrance of the hooked catch-levers 118 beneath the lathing, so that when the upper member 14 is raised said lathing will be lifted by reason of the fact that the hooked ends of the catch-levers 118 will engage under the same near the four corners thereof. As the said upper member 14 rises, the arms 129 will be lifted by the shoulders 121, so as to permit the catch-levers to freely 80 pass upward after which the arms will fall by gravity to the position shown in Fig. 7. The next operation is to release the catch-levers 118 from engagement with the lathing, and to deliver the latter from the press. The mechanism for accomplishing these operations will now be described: Secured on the inner end of the frame 39 are two bars 134, 85 pivotally secured at 135, at the upper end of each of which, is a curved arm 136, each of which curved arms has mounted in bearings 137 at its lower end a sprocket-wheel 138 (see Figs. 4 and 5). Supported on the sprocket-wheels is a sprocket chain 139 which passes to and over a sprocket-wheel 140, mounted on a shaft 141 supported in 90 bearings 142 (Fig. 1). Secured to a base 142^a mounted on the inner side of and extending between two of the uprights 15 are two bars 143 similar to and lying directly 95 opposite the bars 134, and having pivotally secured to their upper ends curved arms 144, on the lower end of each of which is mounted a sprocket-wheel 145, supported on and passing over which is a sprocket chain 146 which 100 passes over a sprocket-wheel 147 on the shaft 141, the two chains 139 and 146 being normally disposed in parallel relation.

Located between each of the bars 134, 143 and the corresponding curved arm pivoted thereto is a leaf-spring 148 which normally 105 tends to press said curved arms inward. Said arms are held away from contact with the upper member 14 of the press by means of contact plates 149 secured on the top of the upper member 14 of the press near the 110 four corners thereof respectively. This position of the parts is shown by Fig. 2. As the upper member 14 is raised the catch-levers 118 will support and carry the lathing section upward, and as this upward movement continues the contact plates 149 will 115 gradually pass off of the curved surface of the arms 136 and 144 and allow the spring 148 to press said arms inward; this not occurring, however, until the lathing has been 120 125 130

carried above the plane of the upper sides of the sprocket chains 139 and 146. When the upper member 14 has reached such an elevated position, the curved arms 136 and 144 will move inward to carry the sprocket chains beneath opposite ends of the lathing. In the continued upward movement of the upper member 14, the crank-arm 126 will strike the arm or stop 127 thereby imparting 10 a part rotation to the rock-shaft 123, which through the medium of the crank-arms 124 and rods 125 will draw the upper ends of the catch-levers 118 inward and allow the section of lathing to fall upon the sprocket 15 chains 139 and 146. The shaft 141 is rotated by means of a belt 150 which passes over a pulley 151 on the main shaft 22 and a pulley 152 on said shaft 141. As the lathing drops, therefore, upon the chains 139 and 20 146, it will be immediately carried out of the machine and delivered upon a suitable support. As the upper member 14 of the press again descends, the contact plates 149 will engage the curved arms 136 and 144 and 25 press them outward, so that the bottom of said upper member of the press will not strike against the sprocket chains. In practice the sprocket chains 139 and 146 will move out of true to such a slight extent as not to interfere with the proper engagement of said 30 chains with their driving sprocket-wheels 140 and 147.

Referring to Figs. 2 and 3, 153 indicates plates which are secured to the sides and ends 35 of the table or bed 12 of the press and project upward a sufficient distance to support the slats located at respective ends and sides of said bed.

I claim:

- 40 1. A machine for weaving slats of definite and substantially uniform length, comprising two members having complementary shed-formers provided with transverse slots, said shed-formers extending in one direction a 45 distance equal to the length of the slats to be woven and in the other a distance equal to the width of the woven article, one of said members being bodily movable in right lines toward and from the other.
- 50 2. A machine for weaving slats of definite and substantially uniform length, comprising two members having complementary shed-formers provided with transverse slots, said shed-formers extending in one direction 55 equal to the length of the slats to be woven and in the other equal to the width of the woven article, and means for bodily moving one of said members in right lines toward and from the other.
- 60 3. A machine for weaving slats of definite and substantially uniform length comprising two members having parallel series of complementary shed-formers provided with transverse slots, said shed-formers extending in one direction a 65 distance equal to the length of the slats to be woven and in the other a distance equal to the width of the woven article, one of said members being movable toward and from the other, means for simultaneously feeding a series of warp-slats onto the stationary mem-

70 of the slats to be woven and in the other a distance equal to the width of the woven article, and means for simultaneously moving all of the shed-formers of one member toward and from the shed-formers of the other mem- 70 ber.

4. A machine for weaving slats of definite and substantially uniform length comprising 75 a lower stationary, and an upper movable member having parallel series of complementary shed-formers provided with transverse slots, said shed-formers extending in one direction a distance equal to the length of the slats to be woven, and in the other a distance equal to the width of the woven article, and means for bodily moving said upper member in right lines toward and from the lower member. 80

5. A machine for weaving slats of definite and substantially uniform length comprising 85 two members having parallel series of stationary complementary shed-formers provided with transverse slots, said shed-formers extending in one direction a distance equal to the length of the slats to be woven and in the other a distance equal to the width of the woven article, and means for bodily moving one of said members toward and from the other. 90

6. A machine for weaving slats of definite 95 and substantially uniform length comprising a lower stationary, and an upper movable member having stationary complementary shed-formers, said shed-formers extending in one direction a distance equal to the length 100 of the slats to be woven, and in the other a distance equal to the width of the woven article, and means for moving one of said members toward and from the other.

7. A machine for weaving slats of definite 105 and substantially uniform length comprising two members each of which is provided with a series of parallel bars equal in length to the length of the warp-slats which are designed to rest thereon, said bars being arranged in 110 apposition and having their opposing faces provided with alternating curved recesses and projections running longitudinally of the bars, said projections having transverse slots and each projection of one bar lying directly 115 opposite a depression of the opposing bar, and means for moving all of the bars of one member simultaneously toward and from the bars of the other member.

8. A machine for weaving slats of definite 120 and substantially uniform length comprising two members having complementary shed-formers provided with transverse slots, said shed-formers extending in one direction a 125 distance equal to the length of the slats to be woven and in the other a distance equal to the width of the woven article, one of said members being movable toward and from the other, means for simultaneously feeding a series of warp-slats onto the stationary mem- 130

- ber and means for simultaneously feeding a series of weft-slats into the sheds formed by the interaction of said shed formers.
9. A machine for weaving slats of definite and substantially uniform length comprising a stationary and a movable member having complementary shed-formers provided with transverse slots, said shed-formers extending in one direction a distance equal to the length of the slats to be woven and in the other a distance equal to the width of the woven article, means for simultaneously feeding a series of warp-slats onto one of said members, means for moving one of said members toward and from the other, and means for simultaneously feeding a series of weft-slats into the sheds formed by the interaction of said shed-formers.
10. In a slat-weaving machine in combination with a lower stationary, and an upper movable member having complementary shed-forming projections provided with transverse slots, means carried by said movable member for lifting the woven lathing, means for automatically releasing said lathing, and movable means for automatically delivering the same from between said members.
11. In a slat-weaving machine in combination with a lower stationary and upper movable member having complementary shed-forming projections provided with transverse slots, pivoted catch-levers carried by said upper member and adapted to raise the lathing with said upper member, means for automatically effecting the disengagement of said catch-levers with said lathing, and traveling carriers adapted to receive said lathing when thus disengaged and to convey the same from between said members.
12. In a slat-weaving machine in combination with a lower stationary and upper movable member having complementary shed-forming projections provided with transverse slots, means carried by said upper member for elevating the lathing therewith, spring - pressed arms supporting sprocket chains at opposite ends of said members, means for rotating said sprocket chains, means carried by said upper member and slidably engaging said arms and adapted thereby to normally hold said sprocket chains free of the upper member, whereby when the upper member is elevated said arms will spring inward and carry said chains beneath the opposite ends of lathing, and means for automatically effecting the release of said lathing to permit it to fall upon said chains and be delivered out of the machine.
13. In a slat-weaving machine in combination with a lower stationary and upper movable member having complementary shed-forming projections provided with transverse slots, a series of spring-controlled levers pivotally mounted on said upper member and having lower hooked ends adapted nor-
- 70 mally to extend inward beyond the outer sides of said upper member and beneath the lathing formed between said members, whereby to lift said lathing with said upper member, means for automatically throwing said hooked ends outward to clear the outer edges of said lower member as the upper member descends and then to permit them to swing inward, means for automatically effecting the disengagement of said catch-levers with the lathing when said upper member has been raised a given distance, and a carrier for receiving the lathing thus released.
- 75 14. In a slat-weaving machine in combination with a lower stationary and upper movable member having complementary shed-forming projections provided with transverse slots, a series of catch-levers pivotally mounted on opposite sides of said upper member and having lower hooked ends adapted to engage beneath the lathing formed between said members and to raise the same with said upper member, a spring-controlled rock-shaft mounted on said upper member, a series of crank-arms thereon, rods connecting said crank-arms with said catch-levers, a stop mounted above said upper member, a crank-arm mounted on said rock-shaft and adapted to engage said stop whereby to rotate the rock-shaft and automatically release the engagement of said catch - levers with the lathing, and a carrier for receiving the lathing thus disengaged.
- 80 15. In a slat-weaving machine in combination with a lower stationary and upper movable member having complementary shed-forming projections provided with transverse slots, means carried by said upper member for raising the lathing formed between said members therewith, means for releasing said lathing when said upper member has reached a predetermined elevation, traveling carriers mounted on opposite sides of said members, and means operating automatically to move said carriers beneath opposite edges of said upper member when the latter is raised and to move them from beneath the same when said upper member is lowered.
- 85 16. In a slat-weaving machine, in combination with a shed-forming press a plurality of means for simultaneously feeding a series of warp-slats and a series of weft-slats into said press, each of said means comprising a table having a series of open receptacles mounted over the table with their bottoms located a distance less than the combined width of two slats above the table, a pair of sprocket chains arranged to travel flush with the upper surface of said table, a bar connecting said sprocket chains and adapted to travel over said table in the space provided between the upper surface thereof and the bottoms of said receptacles, and means for rotating said sprocket chains.
- 90 17. In a slat-weaving machine, in combi-
- 95 100 105 110 115 120 125 130

- nation with a shed-forming press, means for simultaneously feeding a series of slats there-to comprising a support adapted to have a series of piles of slats mounted thereon, a 5 pair of parallel sprocket chains, and means for rotating the same, and a feed-bar connecting said sprocket chains and adapted to sweep over the surface of said support in the movement of said chains, whereby to engage 10 the lowermost slat of each pile and feed them forward into the press.
18. In a slat-weaving machine in combination with a shed-forming press, means for simultaneously feeding a series of slats part- 15 way into said press, comprising a pair of parallel sprocket chains and means for rotating the same, and a bar connecting said sprocket chains, and means for completing the feed of said slats comprising a movable slat-engaging 20 device mounted adjacent to said press, and means adapted to be engaged by said bar for actuating said slat-engaging device.
19. In a slat-weaving machine, in combination with a shed-forming press, means for simultaneously feeding a series of slats part- 25 way into said press comprising two parallel sprocket chains, means for rotating the same, and a bar connecting said chains, means for completing the feed of said slats comprising 30 a rock-shaft mounted adjacent to said press and carrying a slat-engaging device, and a spring-controlled cam finger mounted on said rock-shaft and adapted to be engaged by said bar.
35. 20. In a machine for weaving slats of definite and substantially uniform length, in combination with a holder for warp slats, a shed-forming press having an upper movable member, mechanism for automatically and 40 simultaneously feeding successive series of
- warp slats from said holder to said press, mechanism for lowering said upper member, a holder for weft slats, mechanism for automatically and simultaneously feeding a series of weft slats from said holder to said 45 press, mechanism for raising said upper member, and means for actuating said mechanism in stages and in the order named.
21. In a machine for weaving slats of definite and substantially uniform length, in combination with a holder for warp slats, a shed-forming press having an upper movable member, mechanism for automatically and simultaneously feeding successive series of warp slats from said holder to said press, mechanism for lowering said upper member, a holder for weft slats, mechanism for automatically and simultaneously feeding a series of weft slats from said holder to said 55 press, mechanism for raising said upper member, a continuously rotating shaft, and means carried thereby for actuating said mechanism in stages and in the order named.
22. In a machine for weaving slats of definite and substantially uniform length, means for automatically feeding successive series of warp-slats thereto, means for simultaneously forming sheds in all the slats of each series throughout their length, and means for automatically feeding successive series of 60 weft-slats through the sheds formed in the respective series of warp-slats.
- In testimony whereof I have hereunto set my hand in presence of two subscribing witnesses.

HENRY W. CARPENTER.
